(57) **CLAIM**

The ornamental design for a power and data receptacle mount, as shown and described.

DESCRIPTION

FIG. 1 is a top, front perspective view of a power and data receptacle mount showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof; and,

FIG. 7 is a left side elevation view thereof.

The power and data receptacle mount is shown with a symbolic break along its length in FIGS. 1–5. The appearance of any portion of the power and data receptacle mount between the break lines forms no part of the claimed design.
